COMBINED ELECTRIC DRILL CHUCK KEY
HOLDER AND IDENTIFICATION TAG

Maxwell Ingram, 15 Hamilton Ave., Dumont, N.J.

Filed Apr. 29, 1959, Ser. No. 55,702

Term of patent 7 years

(Cl. D54—14)

Fig. 1

Fig. 2

Fig. 3

Fig. 4

Figure 1 is a top perspective view of a combined electric drill chuck key holder and identification tag showing my new design;

Figure 2 is a bottom plan view thereof;

Figure 3 is a side elevational view thereof; and

Figure 4 is a top plan view thereof.

The spring is shown fragmentary in Figures 2 and 3 for convenience of illustration only.

I claim:

The ornamental design for a combined electric drill chuck key holder and identification tag, substantially as shown and described.
